UNITED STATES PATENT OFFICE.

HENRY C. MASTERS, OF HAMILTON, BERMUDA.

HOOK.

SPECIFICATION forming part of Letters Patent No. 683,475, dated October 1, 1901.

Application filed December 28, 1900. Serial No. 41,435. (No model.)

To all whom it may concern:

Be it known that I, HENRY C. MASTERS, a subject of the Queen of Great Britain, residing at Hamilton, Bermuda, have invented a certain new and useful Improvement in Hooks, of which the following is a specification.

My invention relates to an improvement in hooks in which the standing part of the hook is mounted in a swivel while the point is hinged to the standing part and adapted to be locked in a lug on the swivel.

The object of my improvement is to provide a hook which may be readily and positively locked when desired without danger of disengagement, while at the same time great additional strength is given to the structure. I attain these objects by the mechanism illustrated in the drawings, in which—

Figure 1 represents a front elevation of my improved hook, and Fig. 2 a top view of the same.

In the drawings, as shown, 1 is the swivel, having a perforated lug 2 for engaging the pointed member of the hook.

3 is the standing part of the hook, and is held in the swivel by head 4 or other appropriate means.

5 is the hinge or knuckle on which the pointed member 6 of the hook rocks.

7 represents means for locking the pointed member 6 in the lug 2, so that no accidental upward thrust will disengage the same.

To disengage the point from the lug, it is first necessary to open the point by displacing means 7. Then an upward thrust will cause the point to pass out of the lug, while at the same time it rocks away from the same on knuckle 5. The hook may then be turned in any direction permitted by the swivel, and is

reengaged with the lug by bringing the point 40 over the perforation in the lug and pulling downward. It is thus seen that not only is the point locked to the swivel, but the hook is held rigidly in the same, while the strain on the hook is more evenly distributed than 45 heretofore.

It is obvious that different means may be employed to lock the point and that the knuckle may be done away with if sufficient play is allowed the standing part of the hook 50 in the swivel.

I do not wish to restrict myself to the details shown; but

What I desire to secure and claim by Letters Patent of the United States is—

1. The combination of a swivel having a perforated lug integral therewith, with a hook depending from the swivel, said hook being provided with means adapted to detachably engage the lug, substantially as set forth. 60

2. The combination of a swivel having a perforated lug integral therewith, with a hook depending from the swivel, said hook having a rocking member adapted to detachably engage the lug, substantially as set forth. 65

3. The combination of a swivel having a perforated lug integral therewith, with a hook depending from the swivel, said hook having a rocking member and being provided with means for positively locking the same into 70 said lug, substantially as set forth.

In witness whereof I have hereunto signed my name, in the presence of two witnesses, this 28th day of November, 1900.

HENRY C. MASTERS.
